FLEXIBLE MULTIBLADED ROTOR ASSEMBLY FOR CYLINDER GRINDING MACHINES

Alfred Rebman, Richmond Hill, N. Y., assignor to Rockwood & Co., Brooklyn, N. Y., a corporation

Application July 27, 1945, Serial No. 607,418

9 Claims. (Cl. 241—102)

1

The present invention relates to grinding, refining and mixing machines and more particularly to grinding machines of the Bramley type for grinding, refining and mixing chocolate, cocoa beans and other materials.

One object of the present invention is to provide grinding means of improved action whereby to increase the output of the grinding machines provided with said grinding means. More particularly, pursuant to this object of the invention, the grinding means comprises a plurality of members each of which is provided with a plurality of grinding elements individually engageable with the grinding surface of the cylinder of the machine.

The above and other objects of the invention, which might hereinafter appear, will be fully understood from the following description considered in connection with the accompanying illustrative drawings.

In the drawings:

Fig. 1 is an end view of a grinding unit embodying the present invention, a part of the cylinder of the machine and a portion of the rotor being shown in section;

Fig. 2 is a sectional view on the line 2—2 of Fig. 1;

Fig. 3 is a side view of one of the grinding members;

Fig. 4 is an end view of the grinding member;

Fig. 5 is an inner face view of part of one of the grinding units as seen from the line 5—5 from Fig. 2, and also shows one of the cylinder heads.

In the machine to which the present invention relates, there is a rotor which is in the form of a spider having a plurality of arms, each carrying a grinder unit at its outer end, the grinding elements of the unit being engageable with a cylindrical grinding surface provided on the inner surface of the cylinder of the machine, for example, as shown in U. S. Patent No. 1,740,194 granted December 17, 1929, to Bramley-Moore. In Fig. 1 of the drawings accompanying the present specification there is shown the outer end portion 10 of one of the arms of the spider, and a part of the cylinder C which is provided with a grinding surface which is engaged by the grinding elements of the grinding unit which is carried by arm 10.

The outer end of the spider arm has a slot 14 for supporting the grinding unit for adjustment radially of said arm. A bar 16 which extends longitudinally of the cylinder C has its intermediate portion slidably mounted in slot 14 for movement radially upon 10, said intermediate portion

2

of bar 16 being secured to a center block 18 similarly slideable in slot 14 radially of arm 10.

A plurality of cross members or grinder heads 20 are secured to bar 16. As shown by the drawings the cross members 20 are arranged in pairs disposed transversely of and in spaced relation longitudinally of bar 16 and with the companion cross members 20 of each pair disposed in spaced relation circumferentially of the cylinder C or transversely of bar 16. Cross members 20 are pivotally mounted on the companion longitudinally extended rods 22. A laminated spring 24 is secured between its ends to bar 16 and at its opposite ends to the spaced rods 22, respectively, there being a pair of said laminated springs for each pair of cross members 20, the latter being positioned between said pair of springs, as illustrated in Fig. 5.

The grinding unit comprises a plurality of grinding members 26 which extend longitudinally of the cylinder. Each of said grinding members 26 is secured to a set of longitudinally spaced cross members 20. As illustrated in Figs. 1 and 5, the grinding members 26 are arranged in sets of four on each member 20. It will be understood that the number of grinding members 26 in each set may be different from that shown.

An important feature of the present invention resides in the construction of the grinding members 26. In this respect each grinding member 26 comprises a plurality of, here shown as 3, steel blades 28, 30 and 32 having their outer end portions arranged in spaced confronting relation. Said grinder blades 28, 30, 32 are transversely flexible and are held in spaced relation at their outer lateral portions by interposed spacing members 34 which are also preferably formed of steel, said members 34 being preferably of the same length as said grinding blades. The grinding member 26 also comprises a reinforcing bar 36 which is secured by rivets 38 or any other suitable material to the grinding blades and to the interposed spacing members 34. Thus, the inner lateral portions of said blades are rigidly secured together. As here shown, the grinding blades of each grinding member 26 are each formed in one piece but it will be understood that each of said grinding blades may be formed of longitudinally extending sections secured in the grinding member by bar 36 and the companion securing rivets and likewise it will be understood that the spacing members 34 can be formed of longitudinally extending sections instead of being in one piece. It will be understood also that the grinding blades and the interposed spacing numbers are provided

with registering holes for the shanks of the securing rivets 38. Also, as illustrated in Fig. 3, the grinding member is provided with registering holes 40 for the shanks of rivets 42 by which the grinding members 26 are secured to the cross members 20.

The grinding members 26 are positioned in the recess formed in the cross members 20, each of said recesses being defined by flat surfaces 41 and 43 which as shown in Fig. 1 are at right angles to each other. Holes 44 are provided in the cross members 20 for the shanks of the rivets 42 by which the grinding members 26 are secured to said cross members. It will be noted that the recesses defined by the companion surfaces 41 and 43 are spaced longitudinally of the companion cross member 20 and are open or confront the cylindrical grinding surface 12, and further it will be noted that as shown in Fig. 1 the surface 41 against members 20 position the grinding members so that the several blades thereof lie in planes which intersect the radial plane of the cylinder forming acute angles therewith, the said acute angles being at the sides of the blades which face the direction of rotation, as indicated by the arrow A, of the spider or rotor arm 10 about the axis of the cylinder.

Thus, it will be observed that each grinding member 26 comprises a plurality of blades having inner portions rigidly secured to companion portions of the cross members 20, with interposed spacing means constituted by the spacing members 34, and that each grinding member 26 has outer transversely flexible portions disposed in parallel face to face spaced relation and terminate in grinding edges which are offset from each other laterally of the grinding member and engage the grinding surface 12 in acute angular relation thereto. The grinding members 26 are pressed resiliently against said cylindrically grinding surface 12 by the laminated springs 24. The pressure on springs 24 may be regulated, for regulating the pressure of the grinding members 26 on cylindrical surface 12 in any suitable way, preferably by the means illustrated in the abovementioned patent, said means including a rod 44 mounted for radial movement in arm 10 and bearing on longitudinal bar 16. More particularly, as shown in said patent and as illustrated in Figs. 1 and 2, the outer end of rod 44 extends into a cylindrical opening 46 in slide member 18 and bears against a wearplate 48 which is positioned in said opening and is interposed between the outer end of rod 44 and the adjacent side of bar 16.

The cylindrical grinding surface 12 may be formed in any suitable way, for example, as shown in the abovementioned patent, or as in the patent to McIntyre No. 1,564,427 or as in the patent to Bramley-Moore No. 1,692,884, or as in the patent to McIntyre No. 1,838,565. It will be understood, however, that reference to the cylindrical grinding surfaces such as those shown by the patents herein referred to are not exhaustive of the constructions of the cylindrical grinding surfaces provided for co-action with the grinding members 26 of the present invention. As here shown, cylindrical grinding surface 12 comprises alternate steel strips 50 and hard fiber or non-metallic flat strips 52 disposed in abutting face to face relation in position completely around the inner surface of the cylinder C. Strips 50 and 52 extend substantially for the full length of the cylinder C between the opposite cylinder heads and are disposed edgewise in planes extending radially of the

cylinder. By way of illustration, members 50 are formed of $\frac{1}{8}$ " thick spring steel stock and members 52 are about $\frac{1}{32}$ " thick.

It will be understood that various changes in the details of construction and in the arrangement of parts may be made without departing from the underlying idea or principles of the present invention within the scope of the appended claims.

10. Having thus described my invention, what I claim and desire to secure by Letters Patent is:

1. A grinding member of the character described comprising a plurality of longitudinal blades having longitudinal grinding edges, said blades being disposed in face-to-face confronting relation and secured in said relation with spacing means interposed between said blades, said spacing means terminating in spaced relation to the longitudinal grinding edges of said blades, the portions of the blades extending laterally thereof between said spacing means and said grinding edges being individually flexible, said grinding edges being offset from each other laterally of the grinding member, and a longitudinal reinforcing bar secured to said blades laterally inwardly of said flexible portions.

2. Grinding means of the character described for coaction with a cylindrical grinding surface, said means comprising a rod, a member pivotally mounted on said rod, said member extending in the direction of the circumference of said cylindrical surface and provided with a plurality of recesses confronting said surface, and a plurality of grinding members secured to said member and extending transversely thereof, said grinding members being positioned in said recesses, respectively, each of said grinding members having a plurality of longitudinally extending transversely flexible outer portions disposed in parallel face-to-face spaced relation and terminating in cylinder-engaging grinding edges.

3. Grinding means of the character described for coaction with a cylindrical grinding surface, said means comprising a rod, a member pivotally mounted on said rod, said member extending in the direction of the circumference of said cylindrical surface and provided with a plurality of recesses confronting said surface, and a plurality of grinding members secured to said member and extending transversely thereof, said grinding members being positioned in said recesses, respectively, each of said grinding members comprising a plurality of longitudinal blades disposed in confronting face-to-face relations and having their inner portions rigidly secured in said relation with interposed spacing means, the outer portions of said blades being transversely flexible and having their confronting faces in laterally spaced relation and terminating in cylinder-engaging grinding edges.

4. Grinding means of the character described for coaction with a cylindrical grinding surface, said means comprising a rod, a member pivotally mounted on said rod, said member extending in the direction of the circumference of said cylindrical surface and provided with a plurality of recesses confronting said surface, each of said recesses being defined by a pair of wall surfaces disposed in right-angular relation, and a plurality of grinding members positioned in said recesses, respectively, each of said grinding members having a plurality of confronting laterally spaced parallel flat portions having surfaces lying in planes intersecting the radial plane of the cylindrical grinding surface, one of said wall surfaces being par-

allel to said intersecting planes for positioning the cylinder-engaging edges of said grinding members in angular relation to said cylindrical grinding surface.

5. Grinding means of the character described for coaction with a cylindrical grinding surface, said means comprising a rod, a member pivotally mounted on said rod, said member extending in the direction of the circumference of said cylindrical surface, and a plurality of grinding members secured to said member, each of said grinding members comprising a plurality of longitudinal blades extending transversely of said member, said blades being disposed in face-to-face confronting relation and secured in said relation with spacing means interposed between said blades, said spacing means terminating in spaced relation to the longitudinal grinding edges of said blades, the portions of the blades extending laterally thereof between said spacing means and said grinding edges being individually flexible, said grinding edges being offset from each other laterally of the grinding member.

6. Grinding means of the character described for coaction with a cylindrical grinding surface, said means comprising a rod, a member pivotally mounted on said rod, said member extending in the direction of the circumference of said cylindrical surface, and a plurality of grinding members secured to said member, each of said grinding members comprising a plurality of longitudinal blades extending transversely of said member, said blades being disposed in face-to-face confronting relation and secured in said relation with spacing means interposed between said blades, said spacing means terminating in spaced relation to the longitudinal grinding edges of said blades, the portions of the blades extending laterally thereof between said spacing means and said grinding edges being individually flexible, said grinding edges being offset from each other laterally of the grinding member, said members having means for positioning said blades in planes intersecting the radial plane of the cylindrical grinding surface with all of the grinding edges of said blades in engagement with said cylindrical grinding surface.

7. In a grinding machine of the character described having a cylindrical grinding surface and a rotor co-axial with said cylindrical grinding surface, a grinding unit carried by said rotor and comprising a plurality of grinding members extending longitudinally of the cylinder and disposed in circumferentially spaced relation adjacent to said grinding surface, each of said grinding members being mounted for pivotal movement about an axis parallel to the axis of said cylindrical surface and comprising a plurality of longitudinal blades extending longitudinally of said cylinder and disposed in confronting face-to-face relations and having their inner portions rigidly secured in said relation with interposed spacing means abutting confronting faces of adjacent blades, the outer portions of said blades being transversely flexible and having their confronting faces in laterally spaced relation and terminating in cylinder-engaging grinding edges, the outer portions of said blades being disposed in

planes which intersect the radial planes of said cylinder at acute angles in the direction of rotation of said rotor.

8. In a grinding machine of the character described having a cylindrical grinding surface and a rotor co-axial with said cylindrical grinding surface, a grinding unit carried by said rotor and comprising a plurality of grinding members extending longitudinally of the cylinder and disposed in circumferentially spaced relation adjacent to said grinding surface, each of said grinding members being mounted for pivotal movement about an axis parallel to the axis of said cylindrical surface and comprising a plurality of longitudinal blades extending longitudinally of said cylinder and disposed in confronting face-to-face relations and having their inner portions rigidly secured in said relation with interposed spacing means abutting confronting faces of adjacent blades, the outer portions of said blades being transversely flexible and having their confronting faces in laterally spaced relation and terminating in cylinder-engaging grinding edges, the outer portions of said blades being disposed in planes which intersect the radial planes of said cylinder at acute angles in the direction of rotation of said rotor, means movable radially of said rotor, and a flexible connection between said radially movable means and said grinding members for resiliently pressing the grinding edges of said blades against said grinding surface under the control of said radially movable means.

9. In a grinding machine of the character described having a cylindrical grinding surface and a rotor co-axial with said cylindrical grinding surface, a grinding unit carried by said rotor and comprising a plurality of grinding members extending longitudinally of the cylinder and disposed in circumferentially spaced relation adjacent to said grinding surface, each of said grinding members being mounted for pivotal movement about an axis parallel to the axis of said cylindrical surface and comprising a plurality of longitudinal blades extending longitudinally of said cylinder and disposed in confronting face-to-face relations and having their inner portions rigidly secured in said relation, the outer portions of said blades being transversely flexible and having their confronting faces in laterally spaced relation and terminating in cylinder-engaging grinding edges, means movable radially of said rotor, and a flexible connection between said radially movable means and said grinding members for resiliently pressing the grinding edges of said blades against said grinding surface under the control of said radially movable means.
